UNITED STATES PATENT OFFICE.

GEORGE S. BALL, OF WASHINGTON, DISTRICT OF COLUMBIA, ASSIGNOR TO EDWARD R. MELTON AND JOHN C. JENKINS, BOTH OF WASHINGTON, DISTRICT OF COLUMBIA.

LINER-TRIMMING GAGE.

1,397,612.

Specification of Letters Patent.

Patented Nov. 22, 1921.

Application filed March 24, 1920. Serial No. 368,369.

To all whom it may concern:

Be it known that I, GEORGE S. BALL, a citizen of the United States, residing at Washington, in the District of Columbia, have invented new and useful Improvements in Liner-Trimming Gages, of which the following is a specification.

This invention relates to improvements in gages and more particularly to gages for use in trimming type casting machine liners.

In ejecting the liners from the machine, the ejecting mechanism forcibly strikes the end of the liner and frequently mutilates said end. It is the main object of this invention to provide a gage with which the liner end can be trimmed by filing, so that the mutilated portion of the liner may be removed.

Another object of the invention is to furnish a gage of this character constructed to permit operation on a plane end liner or on a liner having a projecting lug at the end.

A still further object is to provide a liner trimming gage having an adjustable stop member and means for fixing the same for whole or half em adjustments.

With the foregoing objects outlined and with other objects in view, which will appear as the description proceeds, the invention consists in the novel features herein-after described in detail, illustrated in the accompanying drawing and more particularly pointed out in the appended claims.

Referring to the drawing:—

Figure 1 is a top plan view of the gage with a plane end liner located thereon.

Fig. 2 is a side view of the same.

Fig. 3 is a front end view.

Fig. 4 is a similar view but showing a liner having an end projection or lug.

Fig. 5 is a top plan view of the gage showing a liner, having an end lug placed thereon.

Fig. 6 is a perspective view of an end of a plane end liner, a portion of the body of the gage, the end plate of the gage, and a screw for securing the end plate to the body.

Fig. 7 is a detail sectional view of the lug gage attachment used in trimming the end of a liner having a projecting end lug.

Fig. 8 is a perspective view of the lug end of one type of liner.

In the drawing 1 represents a body plate of any suitable material, preferably metal. This plate is of oblong shape and it has a

longitudinal recess 2 in its upper surface, which merges into a groove 3 that extends along one side of the recess.

The distance between the inner surfaces 4 of the side walls 5 of the recess is substantially the same as the width of a liner, so that a standard liner may be inserted in the recess and slid along the same.

The groove 3 receives the longitudinal rib 6 which extends along one face of one type 65 of liner 7.

The top face of the body 1 is calibrated as shown at 8 and the distance between each two lines 9 is equal to a full em. A series of apertures 10 are located between the lines 9 70 and each of these apertures is located a full em from adjacent apertures.

A gage stop member 11 co-operates with the lines 9 and apertures 10 for gaging the length of material to be removed from a liner, and this member is provided on its underside with depending pins 12 and 13, the axis of the former being located one em distance from the edge 14 and the axis of the latter being arranged one-half em distance from the edge 15. The pins are spaced two ems apart and the edges 14 and 15 are arranged three and one-half ems apart. The first edge is flush with the edge 16 of a lateral lug 17 and the edge 15 is flush with the 85 edge 18 of an oppositely extending lateral lug 19.

These latter lugs function as gage stops for the transverse flange 20 which extends across one face of a liner.

Located at the front end of the body is a guide stop plate 21, which has fixed pins 22 that enter recesses in the forward face of the body, and this plate is secured in position by means of a screw 23.

The plate is formed of a suitable tough substance such as hardened steel and it is provided with a rectangular aperture 24 which merges into a depending notch 25. The area of the aperture is substantially the same as the cross-sectional area of a liner with its flange 20 and the notch 25 registers with one end of the groove 3 to accommodate the longitudinal rib 6 on one type of liner.

As best seen from Fig. 7, the front end of the body 1 is provided with a longitudinally extending hole 26 in which is located a piston 27 provided at one end with an extension 28 that can be projected through a bearing 29 in the guide plate 21 to form a pro-

jecting gage for the lug 30 which extends from the end of certain types of liners 7^a. The piston 27 is urged forward by a spring 31 and a locking device such as a screw 32 is used to secure the piston in retracted or projected position.

In operation, assuming that it is desired to trim the mutilated end of a plane ended liner, the member 11 is first removed. Then 10 the liner 7 is placed in the recess 2 and the rib 6 is inserted in the groove 3. After this, the mutilated end of the liner is moved forward until the mutilated portion extends through the plate 21 and projects beyond the 15 forward face of the same. The pins 12 and 13 are then placed in the proper holes 10 to bring the gage edge of one of the lateral lugs 17 or 19 into engagement with the rear wall of the transverse rib 20 of the liner. As 20 shown in Fig. 1, the edges 15 and 18 are in alinement with one of the lines 9 but by reversing the member 11 and placing the pins in the same holes, the edges 14 and 16 may be brought into alinement with the axis of the 25 hole directly forward of said line 9.

After the stop member 11 has been set to hold the mutilated end of the liner in position beyond the front face of the plate 21, the mutilated portion may be operated upon 30 by a file or the like for evening the damaged end. As the plate 21 is of hardened steel or similar non-abrasive substance, the file or trimming implement will not affect the same and the damaged end of the liner may be 35 filed down even with the front face of the plate.

The adjustable lug 28 is also of hardened steel or the like and in projected position, it alines with the end lug 30 of the liner 7^a, 40 so that the damaged end of this type of liner may be smoothed or planed without mutilating the lug 30.

From the foregoing, I believe that the 45 construction and operation of my device will be readily understood without further description, and I am aware that various changes may be made in the construction shown without departing from the spirit of the invention as set forth in the following 50 claims.

What I claim and desire to secure by Letters Patent is:—

1. A device for use in trimming a mutilated end of a type casting machine liner 55 comprising a flat supporting plate for the liner provided at one end with a non-abrasive plate having an aperture through which the mutilated end of the liner is to project, and means coöperating with the supporting 60 plate and engageable with the other end of the liner for fixing the distance that the liner end is to project beyond said non-abrasive plate.

2. A device for use in trimming a mutilated end of a type casting machine liner 65

comprising a flat supporting plate for the liner provided at one end with a non-abrasive plate having an aperture through which the mutilated end of the liner is to project, and adjustable means mounted on the supporting plate and engageable with the other end of the liner for fixing the distance that the mutilated end is to project beyond said non-abrasive plate. 70

3. A device for the use in trimming a mutilated end of a type casting machine liner, comprising a supporting plate for the liner provided with a non-abrasive surface beyond which the mutilated end of the liner is to project, a series of apertures provided in the supporting plate, and a stop member provided with pins which slidably engage said apertures for fixing the distance that the liner end is to project beyond said surface, 75 said pins being unsecured to the plate. 80

4. A device for use in trimming a mutilated end of a type casting machine liner, comprising a supporting plate on which the liner is adapted to rest, a non-abrasive plate provided at one end of the supporting plate and provided with means to permit a liner resting on the supporting plate to be projected beyond the non-abrasive plate, a series of spaced apertures arranged along one side of the supporting plate, and a stop member 90 having a plurality of depending pins which engage said apertures, said stop member having a plurality of oppositely extending lugs, the vertical edge of one of said lugs being spaced a half em from the axis of one 95 of said pins and the opposite vertical edge of the other lug being spaced a whole em 100 from the axis of the other pin.

5. A device of the kind defined by claim 4 having an adjustable lug member movable 105 through the non-abrasive plate and designed to form a guide for use in trimming liners having a lug provided at one end.

6. A device for use in trimming a mutilated end of a type casting machine liner, 110 comprising a supporting plate for the liner having a recessed upper surface designed to receive the liner and to permit sliding movement of the liner relatively to the supporting plate, a non-abrasive plate located at one 115 end of the supporting plate and provided with means to permit the mutilated end of the liner to be projected therethrough, a series of apertures located along one side of the supporting plate and each aperture being located a full em from adjacent apertures, a stop plate having depending pins engageable with said apertures, said stop plate being provided with a plurality of oppositely extending lugs, the forward edge 120 of one lug being spaced a half em from the axis of one of said pins and the rear edge of the other lug being spaced a whole em from the axis of the other pin. 125

7. A device of the kind defined by claim 6 130

in which the supporting plate is provided with a spring pressed plunger having a forwardly extending lug designed to be projected through the non-abrasive plate and a screw engaging said plunger for locking said plunger in adjusted positions.

8. A device for use in trimming a mutilated end of a type casting machine liner, comprising a flat supporting plate, shaped to permit a liner to lie upon the same and provided at one end with a non-abrasive plate having an aperture through which the mutilated end of a liner is to project, a longitudinally disposed series of apertures provided along the plate, and a stop member

provided with a plurality of depending pins which are slidably engageable with a plurality of said apertures and designed to engage the other end of the liner for fixing the distance that the mutilated end of the liner is to project beyond said non-abrasive plate, said pins being in frictional engagement only with said supporting plate in order that they may be adjusted in the apertures which they occupy without altering or unlocking any securing means.

In testimony whereof I have hereunto set my hand.

GEORGE S. BALL.
